US00D747262S

(12) **United States Design Patent**
Cai et al.

(10) **Patent No.:** US D747,262 S
(45) **Date of Patent:** ** Jan. 12, 2016

(54) **PHOTOVOLTAIC BACK PANEL**(71) Applicant: **Dow Global Technologies LLC**,
Midland, MI (US)(72) Inventors: **Jie Cai**, Shanghai (CN); **YongJin Guo**,
Shanghai (CN); **Zhiqing Lin**, Shanghai
(CN)(73) Assignee: **Dow Global Technologies LLC**,
Midland, MI (US)(**) Term: **14 Years**(21) Appl. No.: **29/476,878**(22) Filed: **Dec. 18, 2013**(30) **Foreign Application Priority Data**

Jun. 28, 2013 (CN) 2013 3 0292012

(74) Attorney, Agent, or Firm — Whyte Hirschboeck Dudek
S.C.(57) **CLAIM**The ornamental design for a photovoltaic back panel, as
shown and described.**DESCRIPTION**

FIG. 1 is a perspective view of the photovoltaic back panel;
FIG. 2 is a top plan view thereof;
FIG. 3 is a front elevation;
FIG. 4 is a rear elevation thereof;
FIG. 5 is a left elevation thereof;
FIG. 6 is a right elevation thereof; and,
FIG. 7 is a bottom plan view thereof.
